UNITED STATES PATENT OFFICE.

AUGUST R. SCHOENKY, OF SOMERVILLE, MASSACHUSETTS, ASSIGNOR TO THE REECE SHOE MACHINERY COMPANY, OF BOSTON, MASSACHUSETTS, A CORPORATION OF MAINE.

SEWING-MACHINE.

1,192,004.

Specification of Letters Patent. Patented July 25, 1916.

Application filed October 5, 1915. Serial No. 54,113.

To all whom it may concern:

Be it known that I, AUGUST R. SCHOENKY, a citizen of the United States, residing at Somerville, in the county of Middlesex and State of Massachusetts, have invented certain new and useful Improvements in Sewing-Machines, of which the following is a specification, reference being had therein to the accompanying drawing.

10 This invention relates to sewing machines and is illustrated as applied more particularly to that type of machine used in the manufacture of shoes by the welt system wherein the outsole and welt are sewed together. This is an example of the class of 15 sewing machines wherein one of the work engaging members, usually the presser foot, is clamped or locked against the work. For example, it may be intermittently clamped 20 and released during the stitching, the feed of the work occurring when the clamping pressure is released, and the needle and awl operating when the presser foot is locked upon the work under clamping pressure; 25 there being usually a light pressure imposed upon the presser foot alternately with the heavy clamping action. When such sewing machine is brought to rest in any manner the presser foot, if locked under clamping 30 pressure, will be incapable of being lifted to extract the work.

An object of the present invention is to improve the operation or control of the presser foot of such a machine of the class 35 referred to.

A special object is to enable the presser foot to be opened or lifted at any desired point in the progress of the work.

40 A further object hereof is to obviate the objections to a mechanism such as that shown in my prior Patent No. 1,071,355, wherein a single treadle, when depressed by the operator, serves the double function of, first, releasing the devices which clamp the 45 presser foot in position, and, second, lifting the presser foot. While there is a certain convenience in this one-lever arrangement, it requires complicated connections and is, therefore, liable to disorder. The 50 treadle connections which unlock the presser foot operate during the first part of the treadle's descent and, during the remainder of its descent, these connections are compelled to undergo an excessive, un-

necessary movement. Loose connections or 55 slots are necessary in order that the lifting connections may be inoperative during the unlocking action. Moreover, the fact that both sets of connections are dependent on the same treadle movement requires an accurate 60 adjustment and timing to be constantly maintained. For these several reasons such a presser foot mechanism operated by a single lever has proved generally unsatisfactory.

65 I do not herein broadly claim to be the first to employ two levers, one for unlocking and one for lifting the presser foot. A particular arrangement of two hand levers, for example, is shown in expired Patent No. 70 584,039, wherein one of the levers is rigid with the presser foot arm and extends upwardly, while the other lever is pivoted on the same axis as the presser foot arm, extends upwardly near the first lever and has 75 connections for unlocking the presser foot. With this arrangement the operator is compelled to detach his hand from the shoe and to reach it around so as to grasp both levers, effecting first a pulling motion 80 on the second lever, and then a disadvantageous lifting and pushing motion of the first lever by which he forces the presser foot to swing upwardly. Not only is such arrangement disadvantageous in its 85 construction and in the difficulties of hand operation requiring successive movements in two different directions, but it is, itself, a disadvantage to have the operator devote a hand to this purpose when the hand may be 90 needed for more important functions.

95 It is an object hereof to overcome these defects by providing a particular arrangement of a pair of independent foot levers, independently connected for their separate 100 functions, yet adapted to be put through their operative movements by the motion of a single foot without requiring two directions or species of movement of the foot or other inconvenient action or attention.

Further objects and advantages of this invention will appear in the hereinafter following description.

To the accomplishment of such objects and advantages the present invention consists in the novel mechanism, combinations, arrangements and other features as herein-after illustrated and described.

In the accompanying drawings forming a part hereof Figure 1 is a front elevation of a sole sewing machine embodying the present invention. Fig. 2 is a partial plan view showing the preferred relative arrangement of the two pedals and certain other parts. Fig. 3 is a partial right hand elevation showing the presser foot and associated parts at the top of the machine. Fig. 4 is a view similar to Fig. 3 showing the same parts in a different position. Fig. 5 is a detail view showing one of the parts of the mechanism. Fig. 6 is a right hand elevation of the parts at the base of the machine which are related to this invention. Fig. 7, in front view, shows in detail certain parts of Fig. 6.

Referring in detail to the illustrated machine, the vertical post 11 is shown supported on feet 12 and at its upper end supports the irregular shaped head in which the horizontal main shaft 13 is supported by bearings 14. The shaft 13 has a hand wheel 15 at the left end and a plurality of cams embodied in three rotary disks 16, 17 and 18.

Normally the main shaft, through these cams, effects the movements of the needle and other parts of the stitching mechanism. It will be sufficient to refer to the following parts thereof, since the stitching mechanism *per se* forms no part of the present improvement. A rotary shuttle 19 has its bobbin retained by an arm 20. Beneath the shuttle is a work support 21 above which stands the presser foot 22. These two members are the work engaging members. Preferably the presser foot is the movable one and it is shown as taking the form of a swinging arm which permits it to be either held upon the work or lifted from the work. Any driving mechanism may be employed and a stop motion may be associated therewith. This may be, for example, as generally shown in my prior Patent No. 1,085,093. The driving mechanism may be located in the base and power transmitted by an upright shaft 23 to the main shaft. The stop-motion may be controlled by a knee lever 24 and may include connections shown generally at the left of Fig. 1, as in said prior Patent No. 1,085,093.

The means for intermittently clamping or locking the presser foot during the normal running of the machine include a dog 25 engaging a rack 26 supported at the rear end of an arm 27 which is connected by a powerful spring device 28 with the rearwardly extending arm 29 of the presser foot 22. The arm 29 at its rear end is provided with a second rack 30 engaged by a triple dog 31. Springs 32, 33, tend to hold the dogs against their racks. A cam lever 34 operated from groove 35 in cam disk 17 through stud 36 serves to intermittently clamp and release the presser foot. Dur-

ing the formation of each stitch the lever 34 is forcibly depressed and, after the feeding movement, is forcibly lifted. When the lever 34 is depressed its heel disengages dog 31 while the dog 25, being pivoted to the lever 34, is at the same time disengaged. When the lever is lifted the dog 25 forces upwardly the rack 26 and arm 27 thus imposing the heavy spring pressure of 28 upon the presser foot, whereupon the triple dogs 31 clamp or lock the parts in this position.

For disengaging the dogs to unclamp or unlock the presser foot at other times than upon the lowering of the lever 34 a releasing device or unclamping lever 37 may be used. This is shown mounted loosely upon the same pin or pivot 38 which carries the triple dogs. The lever, shown separately in Fig. 5, is in the form of a bell crank having an upward arm 39 which, when thrown rearward, presses against the pins 40 and 41 of the upper and the lower dogs so as to throw the dogs out of engagement with their racks. This action is effected if the horizontal arm of the lever 37 be depressed. When the presser foot is clamped upon the work the parts are in the position seen in Fig. 3. When the releasing lever has been shifted to release or unclamp the presser foot the dogs become unlocked, as seen in Fig. 4. In this position the presser foot may be lifted. For actuating the releasing lever 37 a downwardly extending rod 42 is shown, this extending to one of the treadles. When the presser foot has been released by pulling down on the rod 42 the presser foot may then be raised by pulling down on a rod 43, the upper end of which is connected with the rear end of the presser foot extension 29. The rod 43 does not extend directly to the presser foot arm but connection is made through a link 44 extending between the presser foot arm and a swinging arm 45 mounted upon a cross shaft 46 which may take part in controlling the amount of thread measured. We thus have very simple connections, namely, a rod 42 directly pivoted to the releasing lever 37 and a rod 43 connected through a link with the presser foot arm 29. By actuating these two rods 42 and 43 successively in this order, the presser foot will first be released and then lifted. This is accomplished herein by a pair of independent pedals which are both engageable by the operator's foot in the same downward movement of his foot, the first pedal being slightly the higher and connected by the rod 42 with the releasing device and the second pedal connected by the rod 43 with the presser foot.

The pedal arrangement is seen in front elevation in Fig. 1, in plan view in Fig. 2, and in right elevation in Fig. 6. The pedal 47, which is connected for releasing the presser foot, is slightly higher than pedal 48

which serves to lift the presser foot. The pedals proper, 47 and 48, both extend transversely, one in front of the other, so that the foot, as indicated in dotted lines, may 5
depress them both in one descending movement. Preferably the higher pedal 47 is to the rear of the other. One of the feet 12 of the machine forms a gage for the foot in finding the pedals. The pedals are out of 10
contact at every point having independent shanks and independent pivots. The shank 49 of pedal 47 preferably extends rearwardly. It may be centrally pivoted at 50 and its rear end may be connected by link 15
51 with a reversing lever 52, which likewise is centrally pivoted at 53 to a fixed frame part, having its farther extremity connected to the rod 42. Depressing pedal 47 thereby causes depression of the rod 42 20
so as to unlock the presser foot before the descending foot depresses the pedal 48. The pedal 48 is at the forward end of a shank or lever 54 which may conveniently extend rearwardly alongside of the shank 49 but 25
out of contact therewith. The shank 54 may be pivoted at its extreme rear 55 quite removed from the pivot 50 of pedal 47. A spring 56 may be employed to normally hold 30
pedal 47 lifted and a similar spring 57 lifts the pedal 48.

The normal operation of these parts may be as follows: When the machine has been stopped at the regular time, or upon an emergency, or otherwise, and assuming the 35
presser foot to be locked upon the work, the operator places his foot in the position indicated in Fig. 2 and depresses it. The preparations may be such for example that a slight depression of three-quarters inch 40
upon the higher pedal 47 is sufficient to effect the unlocking of the presser foot. The continued downward movement of the foot causes the depression of the pedal 48, a five-eighths inch movement of which may be 45
sufficient, to completely lift the presser foot. It will be noted, moreover, that when desired the operator may simply depress the higher pedal 47 with a very little care without moving the other one so as to thereby unlock the presser foot without lifting. On 50
the other hand, after the presser foot has been unlocked, the operator can manipulate the forward pedal 48 without the necessity of paying any attention to the other pedal. 55
The particular pedal arrangement is, therefore, simple, novel, effective and universal in its possibilities of operation.

It will thus be seen that I have described 60
a sewing machine presser foot mechanism attaining the objects and embodying the principles of the present invention. Since many matters of design, arrangement, preparation, combination, connection and detail may be variously modified without 65
departing from the principles involved, it

is not intended to limit the invention to such features, except so far as the same may be enumerated in the appended claims.

What is claimed is:

1. A sewing machine including in combination a work-engaging member or presser foot movable toward and from the work, a clamp adapted to clamp the presser foot against the work during a portion of each stitch, a releasing device adapted when actuated to release the presser foot from such clamping action, and a pair of independent pedals both engageable by the operator's foot in the same downward movement, the first pedal being slightly the higher, connections from the first pedal for actuating said releasing device, and connections from the second pedal for lifting the released presser foot. 70
75
80

2. A sewing machine including in combination a work-engaging member or presser foot movable toward and from the work, a clamp adapted to clamp the presser foot against the work during a portion of each stitch, a releasing device adapted when actuated to release the presser foot from such clamping action, and a pair of independent pedals both engageable by the operator's foot in the same downward movement, the first pedal being slightly the higher, connections from the first pedal for actuating said releasing device, and connections from the second pedal for lifting the released presser foot, said pedals being located one directly in front of the other. 90
95
100

3. A sewing machine including in combination a work-engaging member or presser foot movable toward and from the work, a clamp adapted to clamp the presser foot against the work during a portion of each stitch, a releasing device adapted when actuated to release the presser foot from such clamping action, and a pair of independent pedals both engageable by the operator's foot in the same downward movement, the first pedal being slightly the higher, connections from the first pedal for actuating said releasing device, and connections from the second pedal for lifting the released presser foot, said pedals extending crosswise 110
115
with the higher one to the rear of the other.

4. A sewing machine including in combination a work-engaging member or presser foot movable toward and from the work, a clamp adapted to clamp the presser foot 120
against the work during a portion of each stitch, a releasing device adapted when actuated to release the presser foot from such clamping action, and a pair of independent pedals both engageable by the operator's 125
foot in the same downward movement, the first pedal being slightly the higher, connections from the first pedal for actuating said releasing device, and connections from the second pedal for lifting the released 130
135

presser foot, said pedals extending cross-wise with the higher one to the rear of the other and a fixed part serving as a foot gage.

5. A sewing machine including in combination a work-engaging member movable toward and from the work, means to clamp the same against the work, a first pedal having connections for releasing the clamp-

ing action, and a second pedal having connections for lifting said member, said pedals being independent of each other but arranged to be depressed by the same foot movement so as to first release and then lift the work engaging member. 10

In testimony whereof, I have affixed my signature hereto.

AUGUST R. SCHOENKY. 15
